UNITED STATES PATENT OFFICE.

EDUARD HILGER, OF AIX-LA-CHAPELLE, GERMANY.

DEVICE FOR CLOSING PEDAL-OPENINGS IN PIANOS, PIANOFORTES, &c.

SPECIFICATION forming part of Letters Patent No. 740,853, dated October 6, 1903.

Application filed May 21, 1903. Serial No. 158,215. (No model.)

To all whom it may concern:

Be it known that I, EDUARD HILGER, pianoforte manufacturer, a subject of the King of Prussia, residing at 10 Corneliusstrasse, Aix-la-Chapelle, in the Kingdom of Prussia, Empire of Germany, have invented certain new and useful Improvements in Devices for Closing Pedal-Openings in Pianos, Pianofortes, &c.; and I do hereby declare the following to be a full, clear, and exact description of the invention, such as will enable others skilled in the art to which it appertains to make and use the same.

My present invention relates to a device for automatically closing the pedal-openings in the front wall of a piano, pianoforte, and similar musical instruments necessary for the working of the pedals, so as to effectually prevent mice, insects, and dust from getting into the interior of this class of musical instruments. To this end a plate is slidingly arranged within a casing and hinged to a cross-bar which under the influence of helical springs or other means is following the upward movements of the pedal, and to make this device even in such cases effective when the lifting means have become defective the cross-bar is connected with the pedal by means of a folded band of flexible material serving under normal conditions as a buffer between the cross-bar and pedal; but when said springs or other means are broken or removed, and thus the cross-bar cannot follow the upward movements of the pedal, said band of leather or the like will act as a substitute cover for the pedal-opening until the lifting means can be renewed or repaired.

In the accompanying drawings, Figure 1 is a vertical sectional view taken on line A B of Fig. 2. Fig. 2 is an elevation of the device with the casing partly removed. Fig. 3 is a vertical sectional view similar to the one shown in Fig. 1, showing the pedal in its lowest position. Fig. 4 is a similar view showing the pedal in its highest position, the springs broken, and the flexible band acting as substitute cover.

In order to prevent mice, insects, and dust from getting into the interior of pianos, pianofortes, and similar musical instruments during a time of disuse, it is necessary to provide means which will automatically follow

the pedal when moving upward, and thus cover the opening beneath the pedal when the latter is at rest. To effectually attain this end in view, the pedal *a*, projecting through the opening *b* of the front wall *c* of a piano, pianoforte, and similar musical instruments, is surrounded by a casing *d*, closed at the top and the sides and open at the bottom and, besides this, provided with a front opening *e* to let the pedal *a* pass through. Flush with the lower end of said casing *d* is secured to the front wall *c* a base *f*, provided with two guide-pins *g*, upon which is mov- 65 bly arranged the cross-bar *h*. This cross-bar is connected to the pedal *a* by means of the folded band of leather or of any other suitable material *i* and compelled to follow the upward movements of the pedal under the influence of the helical springs *k*, surrounding said pins *g*, which springs may, if desired, be replaced by weights running over rollers or by other suitable means. To the front of the cross-bar *h* is hinged the plate *l* 75 in such a manner that the front side of this plate is slidingly bearing against the inside of the casing *d* and in addition to this is held to it by the spring *m*, secured to the base *f*, to most effectually exclude the dust. 80 By loosely hinging the plate *l* to the cross-bar *h* binding and undue wear and tear are avoided.

Within the opening *b* of the front wall *c* are placed the felt pads *n* and *o*, of which the former extends into the casing *d* to enlarge the area of contact for the pedal *a* when returned to its upper position by the mechanical means usually employed for this purpose. The pad *o* is narrower than the pad *n*; but both pads serve to prevent noise when the pedal is reaching either of its extreme positions.

Under normal conditions the helical springs *k* will move the cross-bar *h* upward when the pedal *a* is ascending and go down with the cross-bar and pedal when the latter is pressed down, whereby the folded band of leather or of any other suitable material is acting as a buffer between the cross-bar *h* and the pedal *a*, thus preventing any noise, (see Fig. 3; but in case the springs *k* or any other means employed should get broken or become inoperative said flexible band *i* will act as a means

for closing the opening *e*, folding itself up when the pedal is pressed down and unfolding itself when the pedal is ascending, as shown in Fig. 4. Under these conditions the plate *l* will be held in place against the casing *d* and project from the latter through the slot *p*, arranged between the base *f* and lower end of the casing *d*.

Various changes in the details of construction may of course be made without departing from the essential features of my invention, and I therefore desire not to limit myself to the precise construction and arrangement of parts shown herein.

15 I claim—

1. A device for closing pedal-openings in pianos, pianofortes, &c., comprising a stationary casing surrounding the pedal; a cross-bar vertically movable within said casing; means 20 for guiding said cross-bar; a plate attached to said cross-bar; means for compelling the cross-bar and said plate to follow the upward movements of the pedal, and flexible means connecting said cross-bar with the pedal.
2. A device for closing pedal-openings in pianos, pianofortes, &c., comprising a base secured to the front wall of the musical instrument; vertically-arranged pins upon said base; a cross-bar slidingly arranged upon said pins; a plate hinged to said cross-bar; springs 30 surrounding said pins and capable of raising the cross-bar and the plate hinged to the latter to follow the upward motions of the pedal; a flexible band connecting the cross-bar with the pedal folded up to form a buffer between cross-bar and pedal when said springs are op-

erative and serving as a substitute cover when said springs have become inoperative; a stationary casing surrounding said pedal and enclosing said above-named parts of the device; 40 and a spring keeping said hinged plate in sliding contact with the inside of said casing.

3. In a device for closing pedal-openings in pianos, pianofortes, &c., the combination with the pedal; of a stationary casing surrounding 45 said pedal; a base closing the lower end of said casing and secured to the front wall of the musical instrument; guide-pins arranged upon said base; a cross-bar slidingly arranged upon said guide-pins; a plate movably connected 50 with said cross-bar and guided by said base to normally close the opening under the pedal; springs guided by said guide-pins to compel said cross-bar and the plate connected therewith to follow the upward movements of the 55 pedal; a flexible band connecting said cross-bar with said pedal to act under normal conditions as a buffer between said cross-bar and pedal and as a substitute cover when the means for raising said cross-bar and the plate 60 connected therewith have become inoperative; and a spring to keep the plate attached to said cross-bar in sliding contact with the front wall of the stationary casing.

In testimony that I claim the foregoing as 65 my invention I have signed my name in presence of two subscribing witnesses.

EDUARD HILGER.
